UNITED STATES PATENT OFFICE.

JAMES WHITE, OF CLEVELAND, OHIO, ASSIGNOR TO THE NATIONAL SAFE AND LOCK COMPANY, OF SAME PLACE.

METHOD OF FINISHING AND ORNAMENTING SAFES.

SPECIFICATION forming part of Letters Patent No. 374,567, dated December 6, 1887.

Application filed December 12, 1885. Serial No. 185,539. (No model.)

To all whom it may concern:

Be it known that I, JAMES WHITE, a citizen of the United States, residing at Cleveland, in the county of Cuyahoga and State of Ohio, 5 have invented certain new and useful Improvements in Methods of Constructing and Ornamenting Fire-Proof Safes, of which the following is a specification.

Heretofore it has been customary to paint 10 and otherwise ornament the exterior surfaces of safes after they have been filled with the non-conducting and fireproofing material. As the filling with the last said material has occurred prior to the application of the paint or other 15 preserving or ornamenting materials, it has been impossible to use for these purposes any of the coloring materials which require the application of heat for fixing and perfecting them, such as japan. It is well known that 20 metallic surfaces which have been japanned are in many respects superior to those which are merely treated with ordinary paints, and it is the object of this invention, by the use of the process herein described, to render such 25 japanning possible.

In my patent of August 15, 1882, No. 262,872, is shown a safe adapted to be finished and ornamented in accordance with the herein-described method. The safe shown in said patent 30 is filled with the fireproofing material through an aperture cut in the top wall thereof.

The safe is left empty until after the japanning and ornamenting process is completed, and by leaving off one or more of the lowermost plates on the bottom during such process 35 currents of air can be allowed to pass between the inner and outer walls, which currents operate in an advantageous manner both while the safe is being heated and during the cooling operation. After the metal parts of the walls have been secured together, I apply to the safe a coat of japan, after which it is moved into a japanning-oven of any usual or approved construction.

45 At first it is preferable to employ air of a comparatively low temperature, which is gradually raised until the heat has reached about 250° Fahrenheit, more or less, at which temperature the baking will be finished in from

eight to ten hours. The safe is then removed 50 from the oven and allowed to cool, when a second coat of japan is put on, after which it is subjected to the same process as above described. After leaving the furnace the second time and being again cooled, the outer surface 55 of the safe is rubbed with pumice-stone or some similar material, in order to obtain a good surface to apply to the best effect the next coat of japan, which should be of the very best quality. The safe is again baked as 60 before, after which, and after the safe has become cool, it is ready to be filled with the fireproofing material and to be ornamented as desired.

As there is a passage-way between the inner 65 and outer walls of the safe, through which currents of hot air can rise and circulate behind the outer wall, a high degree of heat can be applied to said outer wall and the coat of japan thereon, which very largely aids in driving off 70 the gases from the japanned surfaces, and which expands the metal or opens the pores thereof, so that the japan becomes more thoroughly united thereto.

By following this method of finishing safes 75 I attain many advantages, among which are the following: I save a very large part of the time ordinarily necessary, as it commonly takes ten days, or thereabout, to properly paint and ornament a safe, inasmuch as it must be 80 allowed to dry in the open air on account of the fireproofing material, and if the drying of the paint is hurried too much there is danger of having the paint unevenly distributed and not thoroughly dry, and as a result it cracks 85 and peels off. I am enabled by the use of my process to use to good advantage japan—a material much superior to the ordinary paints.

In carrying out my process a single japanning oven or furnace may be employed, or a 90 series of such furnaces may be employed, the safe being passed from one to another, instead of being replaced in the same oven one or more times.

I do not wish to be understood as claiming 95 to be the first to have applied japan to metal and subsequently bake it, as I am aware that this is a well-known process; but I believe

myself to be the first to have constructed fire-proof safes by following the series of steps herein set forth—that is to say, first constructing the shell of the safe by securing together 5 the sheets of metal which constitute the inner and outer walls of the chambers for the fire-proof material, then, while the said shell is empty, applying the japan and baking it, and finally filling it with the fireproofing material, 10 thereby obviating any attack upon the water of constitution in the said material and imparting to the safes a finish and an ornamentation which cannot be obtained by other methods of construction and ornamenting. This is 15 in contradistinction to the ordinary method of constructing and ornamenting above referred to—namely, first constructing the shell, then filling it with fire-proof material, and finally painting the metal with material which does 20 not require the application of a high heat.

I do not herein claim any of the subject-matter claimed in my other application heretofore filed, No. 110,225, the last said case relating to the oven and furnace by which is carried 25 out part of the process to which the present case relates.

What I claim is—

1. The herein-described method of constructing and ornamenting fire-proof safes, it consisting in first securing together the sheets of 30 metal constituting the inner and outer walls of the chambers for the fire-proof material, then applying japan to the metal surfaces, then subjecting the metal and japan to a baking heat, and finally filling the said chambers 35 with the fire-proof material, substantially as set forth.

2. The herein-described method of constructing and ornamenting fire-proof safes, it consisting in first securing together the sheets of 40 metal which constitute the walls of the fire-proof chamber and causing currents of air to pass through the said chamber, then applying japan to the metal surfaces and subjecting them to a baking heat, and finally filling the 45 said chambers with the fireproofing material, substantially as set forth.

In testimony whereof I affix my signature in presence of two witnesses.

JAMES WHITE.
